UNITED STATES PATENT OFFICE.

ALEXANDER CARSON RUMBLE, OF SAN FRANCISCO, CALIFORNIA, ASSIGNOR
TO THE MIDAS GOLD SAVING MACHINERY COMPANY, OF SAME PLACE.

AMALGAMATOR.

SPECIFICATION forming part of Letters Patent No. 548,595, dated October 22, 1895.

Application filed January 31, 1895. Serial No. 536,842. (No model.)

To all whom it may concern:

Be it known that I, ALEXANDER CARSON RUMBLE, a citizen of the United States, and a resident of San Francisco, in the county of San Francisco and State of California, have invented certain new and useful Improvements in Amalgamators; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a representation of a side elevation of the invention. Fig. 2 is a detail of a portion of amalgam-plate. Figs. 3 and 4 are details of regulator-plate. Figs. 5 and 6 are details of plate G in close relation thereto. Fig. 7 is a cross-section on line $\alpha\alpha$, Fig. 1. Fig. 8 is a central cross-section of cylinder-head. Fig. 9 shows flange on spout of hopper. Fig. 10 is an enlarged cross-section of cylinder-shell, lining or amalgam-plate, and filling or backing.

This invention has relation to certain new and useful improvements in amalgamating-machines; and it consists in the novel construction and combination of parts, all as hereinafter described, and pointed out in the appended claims.

The object of the invention is to provide a machine of the above-named character which will produce a mechanical action of pulp, sand, or other fine material containing free gold upon the amalgamating-surface in such a manner as to secure repeated contacts with such surface without friction or scouring, and at the same time securing contact of the lighter particles of float-gold and floured mercury which persist in floating upon the surface of the water, and consequently cannot be brought in contact with a horizontal amalgamating-plate.

Referring to the accompanying drawings, the letter A designates an elongated cylinder or barrel, which is rotatably supported in suitable bearings $\alpha\alpha$ on a bed Z with its axis inclined to the horizontal, the inclination being such that its receiving end is highest.

This cylinder or barrel is constructed of an outer shell b, usually of sheet metal, an inner lining or amalgam-plate c, of copper, and an interposed filling or backing d. This interposed filling or backing may be of wood or other suitable material; but I prefer that it shall consist of layers of felt between which is placed a composition capable of exciting a constant electrogalvanic action upon the copper amalgam-plate. This composition preferably consists of a combination of sulphate of zinc, copper, carbon, bitumen, and red lead.

The amalgam-plate is formed on its inner face with a series of rigid longitudinal wings or flanges D, which extend the entire length of said plate and which are of considerable breadth, projecting well toward the center of the cylinder or barrel. The number of these wings will depend upon the diameter of the cylinder, a practical size for which I find to be about six feet in length and eighteen inches in diameter. In a machine of this size six or more of the wings or flanges can be used. I do not, however, confine myself to any particular dimensions of the cylinder or number of the wings or flanges. These wings or flanges are formed integrally with the lining or amalgam-plate by crimping the plate in the manner shown in Fig. 2, thus presenting an unbroken surface and avoiding rivets or other fastenings.

Both ends of the cylinder or barrel are closed, its receiving end being provided with a spouted hopper E, which communicates with the interior through the central portion of the head, so that the cylinder or barrel may freely rotate.

Near the discharge end there is provided an interior regulator-plate F, which consists of a central hub portion from which radiate a number of arms or wings F', each of which is formed with one straight edge f and one curved or hooked edge f', giving the end portions of said wings a broad approximately-segmental form. Behind this plate F and in close relation thereto is placed a parallel plate G, of circular form, with a series of radial openings g therethrough. This plate G is formed with an extended hollow axial portion H, which projects through the head of

the barrel or cylinder and forms the journal for the discharge end thereof. Extending through said hollow extension is a rod *h*, which centers the plate *F*, and on the projecting end of which is a hand-wheel or other device whereby the relative position of the plate *F* to the plate *G* may be varied to regulate the discharge.

Beyond the plate *G* the interior of the cylinder or barrel forms a short chamber *I*, the discharge from which consists of a series of openings *J* through the periphery of the cylinder or barrel. *K* is a trough or other receptacle arranged to receive the discharge from said openings.

The axial extension *H* is journaled in a box *L*, which is made vertically slidable in its support, in order to provide for variable adjustments in the inclination of the cylinder or barrel, by means of an adjusting-screw *H'*.

The cylinder or barrel may be rotated by any suitable means, such as the bevel gear-ring *P*, engaged by a pinion *P'* on a driving-shaft *R*, provided with a differential pulley *S*.

To facilitate access to its interior the cylinder is provided with a hinged section *T*. The spout of the hopper where it projects through the head of the barrel or cylinder is formed with a surrounding flange *y*, which turns in a corresponding groove *y'* in a projecting boss *Y* of said head. This end of the barrel also has a semicircular seat in the support *a*, provided with antifriction-rollers *w*, which bear in a groove *w'* of the cylinder.

In operation the longitudinal wings or flanges of the amalgam-plate act as conveyers, continually raising or elevating the pulp and delivering it against the plate at the opposite side, in this manner continually changing the position of the pulp and bringing it repeatedly in contact with the amalgamating-surfaces. The time of passage of the pulp through the cylinder, and consequently the number of contacts with the amalgamating-surface, is governed by the inclination of the barrel or cylinder, its discharge being further regulated by the plates *F* and *G*. The pulp being under the centrifugal action of the rotation will tend to hug the inner surface of the cylinder, and by turning the plate *F* so as to expose only the more central portions of the openings in the plate *G* it will be seen that the discharge will be retarded in proportion to the extent such openings are closed, not only on account of the reduced size of the openings, but owing to the fact that the pulp must be

forced by accumulation against the centrifugal action.

The speed of rotation is usually about forty rotations per minute, but may be varied.

The effect of the electrogalvanic action on the amalgam-plate is to solidify floured mercury and increase the amalgamating properties in the treatment of certain kinds of ores, especially when the gold is coated with iron and other matter.

Having thus described my invention, what I claim as new, and desire to secure by Letters Patent, is—

1. In an amalgamating machine, the combination with a rotatable, inclined amalgamating cylinder, of a discharge regulating plate in the lower portion of said cylinder, said plate comprising a central portion having a series of radiating wings one edge of each of which is curved, a second and parallel plate in close relation to said regulating plate and having a series of radial openings therein, a hollow axial extension on the second plate forming one of the journals of said cylinder, and a rod attached to the regulating cylinder and extending through said extension, substantially as specified.

2. An amalgamator, comprising a hollow inclined cylinder or barrel, rotatably supported, means for adjusting the inclination of said cylinder or barrel, an amalgamating innerlining, comprising a copper plate formed with a series of broad, longitudinal wings or flanges, a hopper arranged to discharge centrally into one end portion of said cylinder and whose spout forms one of the bearings for the cylinder, a discharging chamber at the lower end portion of said cylinder, provided with a series of peripheral discharges, an adjustable regulator for controlling the discharge into said chamber, and gear for rotating said cylinder or barrel, substantially as specified.

3. In an amalgamating machine, the inclined rotary cylinder having a metallic lining formed with a series of broad radial wings or flanges, a discharging chamber at the lower end of said cylinder having a series of peripheral discharges, and an adjustable regulator for controlling the discharge into said chamber, substantially as specified.

In testimony whereof I affix my signature in presence of two witnesses.

ALEXANDER CARSON RUMBLE.
